SIGNAL TRANSLATING CIRCUIT

Charles J. Hirsch, Princeton, N.J., assignor to Radio Corporation of America, a corporation of Delaware

Filed Sept. 21, 1961, Ser. No. 139,633

2 Claims. (Cl. 325—449)

This invention relates to frequency converter or mixer circuits, and more particularly to frequency converter or mixer circuits of the type using negative resistance diodes such as tunnel diodes.

It is an object of this invention to provide a negative resistance diode frequency converter or mixer circuit which exhibits improved noise performance.

The current at signal frequency in the input circuit of a diode converter or mixer is produced by two components. The first component is the current produced by a signal frequency voltage applied to the converter. The second component is the current produced by the conversion of the first component of current to the output frequency and back to the input frequency. In general the two components of current are of a phase to cancel each other, but the second current component is smaller than the first component because of the conversion losses through the diode.

In accordance with the invention, the above noted cancellation effect is used to advantage to provide improved noise performance in a negative resistance diode converter. The noise factor of the frequency converter is determined in part by noise originating at the output frequency due to (1) the diode and (2) the output circuit. In a manner similar to that noted above, the noise current at the output frequency is essentially comprised of two components. The first component of noise current in the output circuit is produced by the noise voltages originating at the output frequency. The second component results from the bilateral nature of diode converters wherein the first component of noise current is converted to the signal frequency, and back from the signal to the output frequency. As mentioned above, the first and second components are in a phase to cancel each other. However the negative resistance of the diode makes it possible for the noise current to be converted from one frequency to another with power gain so that the first and second components of noise current may be made substantially equal so that they may cancel each other.

The relative magnitudes of the first and second components of noise current at output frequency are primarily a function of the average conductance of the diode and the input resistance of the converter. The input resistance r_1 is considered to be the equivalent of the source or generator impedance and the impedance of the converter input circuits tuned to the signal frequency. The average conductance g_o is determined by the D.-C. biasing voltage and the magnitude of the heterodyne oscillator voltage applied to the diode. The first and second components of noise are substantially equal and cancel when the relationship of the input resistance to the average conductance satisfies the condition, $1+r_1g_o=0$. To satisfy this condition g_o must be negative, and this can be achieved by biasing the diode in the negative resistance portion of its current-voltage characteristic.

When the aforesaid condition is satisfied, it has been found that the noise figure of the converter is primarily a function of the D.-C. diode current, I_o , and the average diode conductance, g_o . The higher the absolute value of the ratio of average conductance to the D.-C. diode current, the lower the noise figure. The maximum absolute value of the ratio of the average conductance to D.-C. diode current which may be achieved is a function of the particular diode characteristics. At the present

state of the art germanium tunnel diodes can, if properly operated, provide a higher ratio of $|g_o/I_o|$ than gallium arsenide or other III-V compound diodes.

In the construction of a negative resistance diode frequency converter in accordance with one embodiment of the invention, the diode is biased so as to produce a negative average conductance, and D.-C. bias and local oscillator drive are adjusted to provide the largest value of $|g_o/I_o|$. The input resistance of the converter as defined above is then selected to satisfy the condition $1+r_1g_o=0$. Under these conditions, the first and second components of noise current are of substantially equal amplitude and opposite phase, so they cancel, thereby reducing the noise figure of the converter.

If, in a particular converter circuit design, the condition $1+r_1g_o=0$ is not satisfied, then the converter noise figure is a function not only of the ratio $|g_o/I_o|$ mentioned above, but is also a function of the ratio of the absolute value of the average conductance g_o to the conversion conductance g_c of the diode. The conversion conductance, like the average conductance is a function of the D.-C. bias voltage and the local oscillator drive applied to the diode. It has been found that when the condition $1+r_1g_o=0$ is not satisfied, the smaller the value $(g_o/g_c)^2$, the lower the noise figure. However, g_o should not exceed g_o for stability reasons to be discussed hereinafter.

In accordance with another embodiment of the invention, a frequency converter including negative resistance diode, such as a tunnel diode, is biased in the negative resistance region of its current-voltage characteristic. Since the operating conditions for the maximum value of $|g_o/I_o|$ usually produces very large values of $(g_o/g_c)^2$, for presently available negative resistance tunnel diodes, the D.-C. bias voltage and local oscillator voltage drive are adjusted to provide the maximum value of $|g_o/I_o|$ consistent with a low value of $(g_o/g_c)^2$. In other words the value $|g_o/I_o|$ may not be at the maximum achievable for the particular diode used, but will be at the largest possible value that corresponds to the operating conditions producing a low or near minimum value of $(g_o/g_c)^2$. These operating conditions permit a degree of tolerance so that when the condition $1+r_1g_o=0$ is not satisfied, the noise figure of the converters is not greatly deteriorated.

The novel features that are considered to be characteristic of this invention are set forth with particularity in the appended claims. The invention itself however, both as to its organization and method of operation, as well as additional objects and advantages thereof, will best be understood from the following description when read in connection with the accompanying drawings, in which:

FIGURE 11 is a table showing the noise factor of a frequency converter for various values of D.-C. bias and oscillator voltages applied to the tunnel diode.

One type of negative resistance diode which may be used in frequency converters embodying the invention is known as a tunnel diode. The structural details of such diode are discussed in an article entitled "Tunnel Diodes as High Frequency Devices" by H. S. Sommers, Jr. appearing in the Proc. IRE, p. 1201 et seq., July 1959.

(I) TUNNEL DIODE CHARACTERISTIC

The measured and computed current-voltage characteristics of a typical germanium tunnel diode is shown in FIGURE 1. The current scales depend on the area and doping of the junction, but representative currents are in the milliampere range. In the present case the current scales correspond to the ratio I/I_p , where I is the current through the diode for a given D.-C. bias voltage and I_p is the current maximum at the point p .

For a small reverse voltage the current through the diode increases in the reverse direction as a function of voltage as is indicated by the region b of FIGURE 1.

For small forward bias voltages, the characteristic is substantially symmetrical (FIGURE 1, region c). According to present theory, the forward current results from quantum mechanical tunneling. At higher forward bias voltages, the forward current (believed due to quantum mechanical tunneling) reaches a maximum (at point p), and then begins to decrease. This drop continues (FIGURE 1, region e) to a current minimum point f , and eventually normal injection over the barrier becomes important and the characteristic turns into the usual forward behavior, (region g , FIGURE 1).

The current-voltage characteristic of the diode may be approximated by a power series extending to the 10th order as:

$$i = a_0 + a_1 e + a_2 e^2 + a_3 e^3 + \dots + a_{10} e^{10} \quad (1.1)$$

The conductance of the diode is then:

$$G = \frac{di}{de} = a_1 + 2a_2 e + 3a_3 e^2 + \dots + 10a_{10} e^9 \quad (1.2)$$

The values of a_0 , a_1 , etc., were computed from data obtained from a 1N3218 germanium tunnel diode to be:

$$\begin{aligned} a_0 &= -1.98 \times 10^2 & a_6 &= 1.012 \times 10^5 \\ a_1 &= 4.25 \times 10 & a_7 &= 1.33 \times 10^5 \\ a_2 &= -6.42 \times 10^2 & a_8 &= -8.30 \times 10^5 \\ a_3 &= 3.17 \times 10^3 & a_9 &= 1.17 \times 10^6 \\ a_4 &= -5.27 \times 10^2 & a_{10} &= -5.43 \times 10^5 \end{aligned} \quad (1.3)$$

(II) THE FREQUENCY CONVERTER CIRCUIT

A tunnel diode frequency converter circuit is shown in FIGURE 2. A signal source 10, shown in the dashed rectangle as comprising a signal generator V_g having an internal resistance r_g , generates a voltage $E_g \cos w_1 t$. The signal source 10 represents the equivalent circuit of an antenna, amplifier, or other signal generating or translating means.

Signal voltage from the signal source 10 is applied to the converter tuned input circuit 12. The tuned circuit 12 includes a parallel connected inductor 14 and capacitor 16 resonant at the frequency of the signals supplied by the source 10. In the case where the source 10 comprises an antenna circuit, the tuned circuit 12 is tuned to the

frequency of the signals which are to be received. At resonance the impedance Z_c of the tuned circuit 12 is the resistance of the circuit represented by the resistor r_c connected across the circuit. It should be understood that the resistor r_c may not actually be a physical resistor but represents the resistance of the elements and connections of the tuned circuit 12.

The frequency converter tuned input circuit 12 is connected to a tunnel diode 18 through a conductor 20. The tunnel diode 18 is biased by a battery 22, or other suitable D.-C. source, to the desired operating point as will be described hereinafter. One terminal of the battery 22 is connected to the anode of the diode 18, and the other terminal of the battery 22 is connected through an inductor 24, an output circuit 26, and the input circuit 12 both to the cathode of the diode 18. The D.-C. biasing circuit is shown only by way of example, and may if desired be comprised of a suitable voltage dividing network with a variable resistor to adjust the bias applied to the diode. In practice such a voltage divider network may include a resistor, across which the bias voltage is developed, connected in the D.-C. current path of the diode, and bypassed by a capacitor which offers low impedance to signal and output frequencies. It will be observed that the input and output circuits 12 and 26 offer very little resistance to direct current flow.

A suitable heterodyne oscillation generator 28 supplies an oscillator signal $E_o \cos w_o t$ to an inductive loop 30, which is coupled to the inductor 24. The inductor 24 is tuned to the oscillator frequency by a capacitor 32.

The inductor 24 is connected through a conductor 34 to the output circuit 26. The output circuit 26 is tuned to the intermediate frequency by an inductor 36 connected in parallel with a capacitor 38. The impedance Z_2 of the output circuit at resonance is represented by the resistor r_2 connected across the circuit. As is the case of the input circuit, the resistor r_2 does not necessarily represent a physical resistor.

A common, or ground conductor 40 interconnects the signal source 10, and the input and output circuits 12 and 26 respectively.

(III) GENERAL

To understand the requirements for low noise operation of a tunnel diode frequency converter, the system noise figure will be derived and examined. The system noise figure includes noise contributions by:

- (a) The input circuit at the signal frequency
- (b) The output circuit at the output or intermediate frequency
- (c) The tunnel diode 18 at both frequencies

In order to calculate the individual noise contributions noted above, the relations for linear and conversion conductances for the currents at signal frequency (w_1) and at the output or intermediate frequency (w_2) must be derived, as well as equations for amplification bandwidth, and power gain.

(IV) DETERMINATION OF SIGNAL AND INTERMEDIATE FREQUENCY CURRENTS

For convenience in calculation, the signal source 10 and input circuit 12 portion of the converter circuit is converted by Thevenin's Theorem to that shown in FIG. 3, where all elements are in series. The generated voltage is changed to the voltage appearing across points 2, 8 when connection 2-3 is open; this voltage is

$$\begin{aligned} E_g \cos w_1 t \left(\frac{Z_c}{r_g + Z_c} = \frac{1}{r_g} \frac{r_g Z_c}{r_g + Z_c} = \frac{Z_1}{r_g} \right) &= E_g \frac{Z_1}{r_g} \cos w_1 t \\ &= E_1 \cos w_1 t \end{aligned}$$

The internal impedance of the generator is equal to Z_1 (r_g and Z_c in parallel). This transformation is shown in FIGS. 3 and 4.

The converter action introduces currents at the input signal frequency (w_1) and the output or intermediate

frequency (w_2), so that the total current flowing in the series circuit is generalized:

$$I_T = I_1 \cos w_1 t + I_2 \cos w_2 t \quad (2)$$

The first task of the analysis is to determine I_1 and I_2 . For simplification, assume that $Z_2=0$ for frequencies not equal to the intermediate frequency and $Z_1=0$ for frequencies not equal to the signal frequency.

From FIG. 4, the voltages applied to the diode are seen to be:

(1) A D.-C. bias voltage and a strong local oscillator voltage: 10

$$e_0 = E_0 \cos w_0 t + E_b \quad (2.1)$$

(2) A weak signal voltage: 15

$$e_1 = (E_1 - I_1 Z_1) \cos w_1 t \quad (2.2)$$

(3) A weak reversed I-F voltage: 15

$$e_2 = -I_2 Z_2 \cos w_2 t \quad (2.3)$$

Since e_0 is much larger than e_1 and e_2 , it, e_0 , establishes a dynamic conductance, g , obtained by substituting e_0 for e in Equation 1.2, resulting in:

$$g = a_1 + 2a_2 e_0 + 3a_3 e_0^2 + \dots + 10a_{10} e_0^9 \quad (2.4)$$

expanding $e_0^m = (E_b + E_0 \cos w_0 t)^m$, where $m=1, 2, \dots, 9$, substituting in (2.4), and collecting terms results in:

$$g = g_0 + 2g_c \cos w_0 t + 2g_c^1 \cos 2w_0 t + \dots \quad (2.4.1)$$

If we bind the computation of g_0 and g_c to the first three terms of Equation 2.4 then: 30

$$g_0 = a_1 + 2a_2 E_b + 2a_3 \left[E_b^2 + \frac{E_0^2}{2} \right]$$

$$g_c = [a_2 + 3a_3 E_b] E_0$$

However g_0 , $2g_c$, have been computed for all terms of Equation 2.4 and some values are shown in FIGURE 10, as functions of the D.-C. bias voltage (E_b) and the local oscillator voltage (E_0). 35

Neglecting the term $2g_c^1 \cos 2w_0 t$ for simplicity, the diode is seen to effectively consist of two conductances in parallel, namely: 40

g_0 , a constant conductance producing currents having the same frequency as the voltage applied to it and linearly related to that voltage; and

$2g_c \cos w_0 t$, a conversion conductance, varying at the frequency of the local oscillator, which converts w_1 to $w_2 = w_0 - w_1$, and w_2 to $w_1 = w_0 - w_2$. 45

These two conductances are schematically represented in FIG. 5. 50

(V) VOLTAGE AND CURRENT RELATIONS

From FIG. 5, the total voltage e_D applied to the parallel conductances is seen to be:

$$e_D = (E_1 - I_1 Z_1) \cos w_1 t - I_2 Z_2 \cos w_2 t \quad (3.1) \quad 55$$

e_D produces a current I_A in g_0 equal to

$$I_A = g_0 e_D = g_0 (E_1 - I_1 Z_1) \cos w_1 t - g_0 I_2 Z_2 \cos w_2 t \quad (3.2)$$

e_D produces a current I_B in $2g_c \cos w_0 t$ equal to

$$I_B = e_D \cdot 2g_c \cos w_0 t = 2g_c (E_1 - I_1 Z_1) \cos w_1 t \cos w_0 t \quad (3.3)$$

$$= -2g_c I_2 Z_2 \cos w_2 t \cos w_0 t$$

$$= g_c (E_1 - I_1 Z_1) \cos w_2 t - g_c I_2 Z_2 \cos w_1 t \quad (3.3)$$

The total current I_T through the generator and the load is: 65

$$I_T = I_A + I_B = [g_0 (E_1 - I_1 Z_1) - g_c I_2 Z_2] \cos w_1 t + [g_c (E_1 - I_1 Z_1) - g_c I_2 Z_2] \cos w_2 t \quad (3.4.1)$$

$$= I_1 \cos w_1 t + I_2 \cos w_2 t \quad (3.4.2) \quad 70$$

From 3.4.1 and 3.4.2, the currents at w_1 and w_2 are seen to be:

$$I_1 \cos w_1 t = [g_0 (E_1 - I_1 Z_1) - g_c I_2 Z_2] \cos w_1 t \quad (3.5.1)$$

$$I_2 \cos w_2 t = [g_c (E_1 - I_1 Z_1) - g_c I_2 Z_2] \cos w_2 t \quad (3.5.2) \quad 75$$

Equation 3.5.1 shows that the total current at w_1 is equal to that produced by the voltage $(E_1 - I_1 Z_1) \cos w_1 t$ applied to g_0 , minus the current, produced by $I_2 Z_2 \cos w_2 t$ applied to the conversion conductance g_c , converted to w_1 .

From 3.5.1 and 3.5.2

$$(1 + g_0 Z_1) I_1 + g_0 Z_2 I_2 = g_0 E_1 \quad (3.6.1)$$

$$g_c Z_1 I_1 + (1 + g_c Z_2) I_2 = g_c E_1 \quad (3.6.2)$$

These equations solved for I_1 and I_2 become:

$$I_1 = \frac{g_0 (1 + g_0 Z_2) - g_0^2 Z_2}{(1 + g_0 Z_1) (1 + g_0 Z_2) - g_0^2 Z_1 Z_2} \left(E_1 = E_g \frac{Z_1}{r_g} \right) \quad (3.7)$$

$$I_2 = \frac{g_0}{(1 + g_0 Z_1) (1 + g_0 Z_2) - g_0^2 Z_1 Z_2} \left(E_1 = E_g \frac{Z_1}{r_g} \right) \quad (3.8)$$

By symmetry it is seen that the current $I_2' \cos w_2 t$ produced by a voltage $E_2 \cos w_2 t$ is given by

$$I_2' = \frac{g_0 (1 + g_0 Z_1) - g_0^2 Z_1}{(1 + g_0 Z_1) (1 + g_0 Z_2) - g_0^2 Z_1 Z_2} E_2 \quad (3.9)$$

At resonance, $Z_1 = r_1$; $Z_2 = r_2$ so that

$$I_1 = \frac{g_0 (1 + g_0 r_2) - g_0^2 r_2}{(1 + g_0 r_1) (1 + g_0 r_2) - g_0^2 r_1 r_2} \left(E_1 = E_g \frac{r_1}{r_g} \right) \quad (3.7.1)$$

$$I_2 = \frac{g_0}{(1 + g_0 r_1) (1 + g_0 r_2) - g_0^2 r_1 r_2} \left(E_1 = E_g \frac{r_1}{r_g} \right) \quad (3.8.1)$$

$$I_2' = \frac{g_0 (1 + g_0 r_1) - g_0^2 r_1}{(1 + g_0 r_1) (1 + g_0 r_2) - g_0^2 r_1 r_2} E_2 \quad (3.9.1)$$

The circuit is stable when the total circuit conductance G_1 is positive at w_1 and the total positive circuit conductance G_2 is positive at w_2 or:

$$G_1 = \frac{I_1}{E_1} = \frac{g_0 (1 + g_0 r_2) - g_0^2 r_2 = N_1}{(1 + g_0 r_1) (1 + g_0 r_2) - g_0^2 r_1 r_2 = D} > 0 \quad (3.7.2)$$

and

$$G_2 = \frac{I_2'}{E_2} = \frac{g_0 (1 + g_0 r_1) - g_0^2 r_1 = N_2}{(1 + g_0 r_1) (1 + g_0 r_2) - g_0^2 r_1 r_2 = D} > 0 \quad (3.9.2)$$

(VI) AMPLIFICATION, BANDWIDTH, AND POWER GAIN

Repeating (3.8)

$$I_2 = \frac{g_0}{(1 + g_0 Z_1) (1 + g_0 Z_2) - g_0^2 Z_1 Z_2} E_g \frac{Z_1}{r_g} \quad (3.8)$$

Divide the numerator and denominator by $Z_1 Z_2$

$$I_2 = \frac{g_0 / Z_2}{\left(\frac{1}{Z_1} + g_0 \right) \left(\frac{1}{Z_2} + g_0 \right) - g_0^2} \frac{E_g}{r_g}$$

The output voltage is $I_2 Z_2$ so that the amplification A is

$$A = \frac{I_2 Z_2}{E_g} = \frac{g_0 / r_g}{\left(\frac{1}{Z_1} + g_0 \right) \left(\frac{1}{Z_2} + g_0 \right) - g_0^2} \quad (4.1)$$

For simplification, we will assume the output circuit to be so broadly tuned that $Z_2 = r_2$ over the whole 3 db bandwidth of the converter.

$$\frac{1}{Z_1} \approx \frac{1 - jQ_1 2d / w_1}{r_1} \quad (4.2)$$

where

$$Q_1 = r_1 / w_1 L = r_1 w C_1 \quad (4.2.1)$$

$$d = w_1 - w = \text{departure from res.}$$

Substitute (4.2) as well as $Z_2 = r_2$ in (4.1):

$$A = \frac{I_2 r_2}{E_g} = \frac{g_0 / r_g}{\left(\frac{1 - jQ_1 2d / w_1}{r_1} + g_0 \right) \left(\frac{1}{r_2} + g_0 \right) - g_0^2} = \frac{g_0 / r_g}{\left(\frac{1}{r_1} + g_0 \right) \frac{1}{r_2} + g_0 - g_0^2 - j \left(\frac{1}{r_2} + g_0 \right) \left(\frac{Q_1 2d}{r_1 w_1} \right)} \quad (4.3)$$

At resonance $d=0$, and

$$A = \frac{I_2 r_2}{E_g} = \frac{g_o / r_g}{\left(\frac{1}{r_1} + g_o\right) \left(\frac{1}{r_2} + g_o\right) - g_o^2} \quad (4.3.1)$$

The value of d which reduces A by 3 db is given by:

$$\left(\frac{1}{r_2} + g_o\right) \left(\frac{Q_1}{r_1} \frac{2d_1}{w_1}\right) = \left(\frac{1}{r_1} + g_o\right) \left(\frac{1}{r_2} + g_o\right) - g_o^2 \quad (4.4)$$

Since Equation 4.3 is symmetrical about resonance, the total bandwidth $B=2d_1$. Clearing of fractions:

$$(1+g_o r_2) Q_1 \frac{2d_1}{w_1} = (1+g_o r_1) (1+g_o r_2) - g_o^2 r_1 r_2 \quad 15$$

From 4.2.1; $Q=r_1 w_1 C_1$

$$(1+g_o r_2) r_1 C_1 B = (1+g_o r_1) (1+g_o r_2) - g_o^2 r_1 r_2$$

$$BC_1 = \frac{(1+g_o r_1) (1+g_o r_2) - g_o^2 r_1 r_2}{(1+g_o r_2) r_1} \quad (4.5)$$

The power output P_o at resonance is from (3.8.1)

$$P_o = I_2^2 r_2 = \left[\frac{g_o}{(1+g_o r_1) (1+g_o r_2) - g_o^2 r_1 r_2} \right]^2 E_g^2 \frac{r_1^2}{r_g} r_2 \quad (4.6)$$

The available input power P_a is:

$$P_a = E_g^2 / 4r_g \quad (4.7)$$

so that the power gain G_p is:

$$G_p = \frac{P_o}{P_a} = \left[\frac{g_o}{(1+g_o r_1) (1+g_o r_2) - g_o^2 r_1 r_2} \right]^2 E_g^2 \left(\frac{r_1}{r_g} \right)^2 r_2 \frac{4r_g}{E_g} \quad 30$$

$$= \frac{r_2^2}{r_g} \left[\frac{2g_o r_1}{(1+g_o r_1) (1+g_o r_2) - g_o^2 r_1 r_2} \right]^2 \quad 35$$

From (4.5):

$$(1+g_o r_1) (1+g_o r_2) - g_o^2 r_1 r_2 = (1+g_o r_2) r_1 B C_1$$

Substituting in 4.8:

$$G_p = \frac{r_2}{r_g} \left[\frac{2g_o r_1}{(1+g_o r_2) r_1 B C_1} \right]^2 \quad 50$$

$$G_p B^2 = \frac{r_2}{r_g} \left[\frac{2g_o}{(1+g_o r_2) C} \right]^2 \quad 55$$

$$\sqrt{G_p B} = \frac{2g_o}{(1+g_o r_2) C} \sqrt{\frac{r_2}{r_g}} \quad (4.9)$$

(VII) NOISE

Contribution to noise comes from:

A. The combined resistance (r_1) of the generator and input tuned circuit 12, producing a noise voltage E_{1n} at the signal frequency (w_1).

$$E_{1n} = \sqrt{4KTB r_1} \quad (5.1)$$

where

K =Boltzman's constant

T =Absolute temperature

$B=2\pi$ bandwidth

B. The output load resistance r_2 which produces a noise voltage E_{2n} at the IF frequency w_2

$$E_{2n} = \sqrt{4KTB r_2} \quad (5.2)$$

C. The tunnel diode noise generated at the signal frequency (w_1).

D. The tunnel diode noise generated at the IF frequency w_2 .

(A) Noise generated by the generator and input circuit

Referring to FIGURE 7, the output current I_{2n} produced by $\sqrt{4KTB r_1}$ is obtained by substituting this value for E_1 in Equation 3.8.1 so that:

$$I_{2n}' = \frac{g_o \sqrt{4KTB r_1}}{(1+g_o r_1) (1+g_o r_2) - g_o^2 r_1 r_2} \quad (5.3)$$

This produces an output voltage:

$$V_{2n}' = I_{2n} r_2$$

which when squared becomes

$$(V_{2n}')^2 = (I_{2n} r_2)^2 = \frac{g_o^2 4KTB r_1 r_2^2}{[(1+g_o r_1) (1+g_o r_2) - g_o^2 r_1 r_2]^2}$$

Multiplying by r_g / r_g and regrouping:

$$(V_{2n}')^2 = KTB \left\{ \frac{r_2}{r_g} \left[\frac{2g_o r_1}{(1+g_o r_1) (1+g_o r_2) - g_o^2 r_1 r_2} \right]^2 \right\} r_2 \frac{r_g}{r_1} \quad 10$$

The quantity in the bracket is equal to G_p (see 4.8) so that:

$$(V_{2n}')^2 = KTB G_p r_2 \frac{r_g}{r_1} \quad (5.4)$$

(B) Noise generated by the output circuit at w_2

Referring to FIGURE 7, this circuit produces a thermal noise voltage

$$E_{2n} = \sqrt{4KTB r_2} \quad (5.2)$$

which produces a current:

$$I_{2n}' = \frac{g_o (1+g_o r_1) - g_o^2 r_1}{(1+g_o r_1) (1+g_o r_2) - g_o^2 r_1 r_2} \sqrt{4KTB r_2}$$

The output noise voltage is seen from FIGURE 7 to be

$$V_{2n}'' = E_{2n} - I_{2n}'' r_2 = E_{2n} \left[1 - \frac{g_o r_2 (1+g_o r_1) - g_o^2 r_1 r_2}{(1+g_o r_1) (1+g_o r_2) - g_o^2 r_1 r_2} \right] = E_{2n} \frac{1+g_o r_1}{(1+g_o r_1) (1+g_o r_2) - g_o^2 r_1 r_2} \quad 25$$

$$(V_{2n}'')^2 = KTB r_2 \left[\frac{r_2}{r_g} \left[\frac{2g_o r_1}{(1+g_o r_1) (1+g_o r_2) - g_o^2 r_1 r_2} \right]^2 \right] \left[\frac{r_g}{r_2} \left[\frac{1+g_o r_1}{g_o r_1} \right]^2 \right] = KTB G_p r_2 \frac{r_g}{r_2} \left[\frac{1+g_o r_1}{g_o r_1} \right]^2 \quad 35 \quad (5.5)$$

(C) Noise contributed by the tunnel diode

This noise can be considered to be supplied by a noise current, i_n , from a constant-current generator I_k connected across the diode as in FIGURE 8, and equal to:

$$i_n = \sqrt{2qI_o B} = 20I_o \times 4KTB$$

where

q =the electron charge

I_o =the average D.C. current

$B=2\pi$ times the bandwidth

The diode, local oscillator, and bias are replaced by the two equivalent parallel conductances g_o and $2g_o \cos w_o t$ as shown in FIGURE 8.

By application of Thevenin's Theorem, the constant-current generator, I_k , and the shunt conductance, g_o , are replaced by a constant-voltage generator whose open circuit voltage is i_n / g_o , and whose internal resistance is $1/g_o$ as shown in FIG. 9. Z_1 and Z_2 are assumed to be tuned and become r_1 and r_2 . $Z_k=0$ when $w \neq w_k$.

Assuming $Z_k=0$ when $w \neq w_k$, the image frequency noise can be neglected and only the noise currents at signal frequency, $i_n \cos w_1 t$, and at the intermediate frequency, $i_n \cos w_2 t$, will be considered.

The conversion conductance $2g_o \cos w_o t$ converts noise at w_1 to noise at w_2 and vice versa, so that the total noise current I_{Tn} through the generator V_c is:

$$I_{Tn} = I_{1n} \cos w_1 t + I_{2n} \cos w_2 t \quad (5.7)$$

The voltage e_{ab} across points a, b is equal to that of the generator minus the voltage drop in $1/g_o$, or

$$e_{ab} = \frac{i_n}{g_o} - \frac{I_{Tn}}{g_o} = \frac{i_n}{g_o} - \frac{1}{g_o} (I_{in} \cos w_1 t + I_{2n} \cos w_2 t) \quad (5.8)$$

For noises generated at the signal frequency w_1 and at the IF frequency w_2 , Equation 5.7 becomes

$$e_{ab}' = \frac{i_n - I_{in}'}{g_o} \cos w_1 t - \frac{I_{2n}'}{g_o} \cos w_2 t \quad (5.8.1) \quad 10$$

$$e_{ab}'' = \frac{i_n - I_{2n}''}{g_o} \cos w_2 t - \frac{I_{in}'}{g_o} \cos w_1 t \quad (5.8.2)$$

Consider first the voltage due to noise at signal frequency e_{ab}' . When applied to path C, of the circuit of FIG. 9, it produces a current $I_c = e_{ab}' / (r_1 + r_2)$ but because $r_k = 0$, when $w \neq w_k$, the current really is:

$$I_c = \frac{i_n - I_{in}'}{g_o r_1} \cos w_1 t - \frac{I_{2n}'}{g_o r_2} \cos w_2 t \quad (5.9.1) \quad 20$$

e_{ab}' applied to $2g_c \cos w_0 t$ (path D) produces:

$$I_d = e_{ab}' \cdot 2g_c \cos w_0 t =$$

$$2g_c \cos w_0 t \left(\frac{i_n - I_{in}'}{g_o} \cos w_1 t - \frac{I_{2n}'}{g_o} \cos w_2 t \right) = \\ \frac{g_o}{g_o} (i_n - I_{in}') \cos w_2 t - \frac{g_o}{g_o} I_{2n}' \cos w_1 t \quad (5.9.2) \quad 30$$

The total current through the generator is:

$$I_{Tn} = I_c + I_d = \left(\frac{i_n - I_{in}'}{g_o r_1} - \frac{g_o}{g_o} I_{2n}' \right) \cos w_1 t + \\ \left[\frac{g_o}{g_o} (i_n - I_{in}') - \frac{I_{2n}'}{g_o r_1} \right] \cos w_2 t = I_{in}' \cos w_1 t + I_{2n}' \cos w_2 t$$

from which

$$I_{in} \cos w_1 t = \left(\frac{i_n - I_{in}'}{g_o r_1} - \frac{g_o}{g_o} I_{2n}' \right) \cos w_1 t$$

$$I_{2n} \cos w_2 t = \left[\frac{g_o}{g_o} (i_n - I_{in}') - \frac{I_{2n}'}{g_o r_1} \right] \cos w_2 t$$

These two equations become:

$$(1 + g_o r_1) I_{in}' + g_o r_1 I_{2n}' = i_n \quad (5.10.1)$$

$$g_o r_2 I_{in}' (1 + g_o r_2) I_{2n}' = g_o r_2 i_n \quad (5.10.2)$$

These two equations solved for I_{in}' and I_{2n}' give:

$$I_{in}' = \frac{(1 + g_o r_1) - g_o^2 r_1 r_2}{(1 + g_o r_1)(1 + g_o r_2) - g_o^2 r_1 r_2} i_n \quad (5.11) \quad 55$$

$$I_{2n}' = \frac{g_o g_o r_1 r_2}{(1 + g_o r_1)(1 + g_o r_2) - g_o^2 r_1 r_2} i_n \quad (5.12)$$

The noise current produced by the tunnel diode at w_2 can be derived from (5.11) by inspection and is obtained from it by substituting I_{2n}' for I_{in}' ; r_1 for r_2 ; r_2 for r_1 ; and i_n for i_n . It is:

$$I_{2n}'' = \frac{1 + g_o r_1 - g_o^2 r_1 r_2}{(1 + g_o r_1)(1 + g_o r_2) - g_o^2 r_1 r_2} i_n \quad (5.13) \quad 65$$

The noise output voltage (at w_2) across r_2 , due to the TD at w_1 , is equal to the last term of 5.8.1 or, since $r_1 = 0$ when $w = w_2$:

$$V_{2n}''' = -\frac{I_{2n}'}{g_o} = -\frac{g_o r_2 \sqrt{20 I_o \times 4 K T B}}{(1 + g_o r_1)(1 + g_o r_2) - g_o^2 r_1 r_2} \quad (5.14) \quad 75$$

The noise output voltage (at w_2) across r_2 , due to the TD noise at w_2 , is equal to the first term of Equation 5.8.2 or:

$$V_{2n}''' = \frac{i_n - I_{2n}''}{g_o} = \frac{i_n}{g_o} \left[1 - \frac{1 + g_o r_1 - g_o^2 r_1 r_2}{(1 + g_o r_1)(1 + g_o r_2) - g_o^2 r_1 r_2} \right] \\ = \frac{i_n^2}{g_o} \left[\frac{(1 + g_o r_1)(1 + g_o r_2) - g_o^2 r_1 r_2 - (1 + g_o r_1) + g_o^2 r_1 r_2}{(1 + g_o r_1)(1 + g_o r_2) - g_o^2 r_1 r_2} \right] \\ = \frac{i_n^2}{g_o} \frac{g_o r_2 (1 + g_o r_1)}{(1 + g_o r_1)(1 + g_o r_2) - g_o^2 r_1 r_2} \\ = \frac{r_2 (1 + g_o r_1) \sqrt{20 I_o \times 4 K T B}}{(1 + g_o r_1)(1 + g_o r_2) - g_o^2 r_1 r_2} \quad (5.15)$$

Squaring V_{2n}'''

$$(V_{2n}''')^2 = \frac{g_o^2 r_2^2 r_2^2 20 I_o 4 K T B}{(1 + g_o r_1)(1 + g_o r_2) - g_o^2 r_1 r_2}$$

Multiplying by r_g / r_g and rearranging terms

$$= K T B r_2 \frac{r_2}{r_g} \left\{ \frac{4 g_o^2 r_1^2}{((1 + g_o r_1)(1 + g_o r_2) - g_o^2 r_1 r_2)^2} \right\} 20 I_o r_g \\ = K T B G_p r_2 \cdot 20 I_o r_g \quad (5.16)$$

Squaring V_{2n}'''

$$(V_{2n}''')^2 = \frac{r_2^2 (1 + g_o r_1)^2 20 I_o \times K T B}{[(1 + g_o r_1)(1 + g_o r_2) - g_o^2 r_1 r_2]^2}$$

Multiplying by

$$\frac{r_g}{r_g} \frac{g_o^2 r_1^2}{g_o^2 r_1^2}$$

and rearranging terms

$$(V_{2n}''')^2 = \\ 35 K T B r_2 \frac{r_2}{r_g} \left\{ \frac{4 g_o^2 r_1^2}{[(1 + g_o r_1)(1 + g_o r_2) - g_o^2 r_1 r_2]^2} \right\} 20 I_o r_g \left[\frac{1 + g_o r_1}{g_o r_1} \right]^2 \\ = K T B G_p r_2 20 I_o r_g \left[\frac{1 + g_o r_1}{g_o r_1} \right]^2 \quad (5.17)$$

40 (D) Total (output noise-voltage) ^{2} $- V_T^2$ — from all sources

$$V_T^2 = (V_{2n}')^2 + (V_{2n}'')^2 + (V_{2n}''')^2 + (V_{2n}''')^2$$

from 5.4; 5.5; 5.15; and 5.16

$$45 V_T^2 = K T B G_p r_2 \left\{ \frac{r_g}{r_1} + \frac{r_g}{r_2} \left[\frac{1 + g_o r_1}{g_o r_1} \right]^2 + 20 I_o r_g \right. \\ \left. + 20 I_o r_g \left[\frac{1 + g_o r_1}{g_o r_1} \right]^2 \right\} \quad (5.18)$$

V_T^2 is the sum of all (noise-voltage) ^{2} at the output due to all causes.

The first term is the contribution of the generator and tuned input circuit.

The second term is the contribution of the output circuit.

The third term is the contribution of the tunnel diode at w_1 .

The fourth term is the contribution of the tunnel diode at w_2 .

(E) (Output noise-voltage) ^{2} $- V_{on}^2$ — (due to the available input noise power)

60 The available input noise power is KTB. It produces an output power $K T B G_p$, which produces a voltage V_{on} across the output load r_2 such that:

$$\frac{V_{on}^2}{r_2} = K T B G_p \\ V_{on}^2 = K T B G_p r_2 \quad (5.19)$$

(F) Noise figures of the converter system, including sources of noise at the IF — N_F

70 By definition:

$$N_F = \frac{V_T^2}{V_{on}^2} = \frac{r_g}{r_1} + \frac{r_g}{r_2} \left(\frac{1 + g_o r_1}{g_o r_1} \right)^2 + 20 I_o r_g \\ + 20 I_o r_g \left(\frac{1 + g_o r_1}{g_o r_1} \right)^2$$

Factoring out r_g/r_1 and rearranging

$$N_F = \frac{r_g}{r_1} \left[1 + 20I_o r_1 + \left[\frac{1+g_o r_1}{g_c^2 r_1} \right]^2 \left[\frac{r_1}{r_2} + 20I_o r_2 \right] \right] \\ = \frac{r_g}{r_1} \left[1 + 20I_o r_1 + \frac{[1+g_o r_1]^2 [1+20I_o r_2]}{g_c^2 r_1 r_2} \right] \quad (5.20)$$

(VIII) EXAMINATION OF THE NOISE FIGURE

Since in a tunnel diode g_o can be negative, it is possible to make $g_o = -1/r_1$, then $1+g_o r_1 = 0$, and the formula for the noise figure reduces to:

$$N_F = \frac{r_g}{r_1} [1 + 20I_o r_1] = \frac{r_g}{r_1} [1 + 20I_o / |g_o|] \quad (6.1)$$

Making $1+g_o r_1 = 0$, results in the cancellation of the noise originating at w_2 in the tunnel diode and in the output circuit. The term $r_g/r_1 = 2$ when the generator is matched to the input circuit and $r_g/r_1 = 1$ for a standing wave ratio ($SWR = \infty$).

The term g_o/I_o (in Equation 6.1) depends on the tunnel diode and on its operating parameters. The greater g_o/I_o , the conductance per unit of current, the lower the noise figure becomes.

Presently available tunnel diodes have been found to have a maximum value of $g_o/I_o = 15.1$ so that it results in a value of:

$$N_F = 1 + \frac{20}{15.1} = 3.65 \text{ db.}$$

Referring back to the relation for the noise-figure

$$N_F = 1 + 20I_o r_1 + \frac{(1+g_o r_1)^2}{g_c^2 r_1 r_2} (1 + 20I_o r_2) \quad (5.2)$$

it is seen that if $1+g_o r_1$ is not exactly equal to zero, but equal to say ± 0.1 , then a large value of $g_c^2 r_1 r_2$ is desired to keep the value of N_F low.

It is shown hereinafter that the circuit is stable if:

$$\frac{g_o}{g_c} < 1; 1 < \frac{r_2}{r_1} < \frac{1}{1 - g_c^2/g_o^2} \quad (7.3 \text{ and } 7.4)$$

For values of g_o and g_c calculated for a commercially available tunnel diode type IN3218, r_2/r_1 lies between 1.0+ and 2.3. For simplicity in what follows we will assume that $r_2 = r_1$. Then:

$$N_F = 1 + 20I_o r_1 + \frac{(1+g_o r_1)^2}{g_c^2 r_1 r_2} (1 + 20I_o r_1) \quad (6.2)$$

let

$$1+g_o r_1 = \pm b \text{ and } r_1 = \frac{1}{|g_o|}$$

then after collecting terms:

$$N_F = \left[1 + 20 \frac{I_o}{g_o} \right] \left[1 + b^2 \left(\frac{g_o}{g_c} \right)^2 \right] \quad (6.4)$$

This relation shows that (1) g_o/I_o must be large to reduce the noise figure, and (2) $(g_o/g_c)^2$ must be small to keep the noise figure low when $b \neq 0$.

Referring now to lines 11 and 12 of the table in FIGURE 11, it is seen that $g_o/I_o = 13.0$ (and therefore $N_F = 4.1$ db; for $b = 0$) for two operating conditions, namely:

- (1) $E_b = 0.10V$ and $E_o = 0.01V$
- (2) $E_b = 0.12V$ and $E_o = 0.02V$

However, condition (1) results in $(g_o/g_c)^2 = 12,000$ and, therefore, $N_F = 25$ db for $b = \pm 0.1$; while condition (2) results in $(g_o/g_c)^2 = 78$ and, therefore, $N_F = 6.6$ db again for $b = \pm 0.1$.

(IX) STABILITY

The circuit is stable if:

$$G_2 = \frac{g_o (1+g_o r_1) - g_c^2 r_1}{(1+g_o r_1) (1+g_o r_2) - g_c^2 r_1 r_2} > 0 \quad (3.9.2)$$

and

$$G_1 = \frac{g_o (1+g_o r_1) - g_c^2 r_2}{(1+g_o r_1) (1+g_o r_2) - g_c^2 r_1 r_2} > 0 \quad (3.7.2)$$

Inserting $1+g_o r_1 = 0$ in 3.9.2, results in:

$$G_2 = 1/r_2$$

which is greater than zero.

Inserting $1+g_o r_1 = 0$ in 3.7.2, results in:

$$G_1 = \frac{-(1-r_2/r_1)/r_1 - g_c^2 r_2}{-g_c^2 r_1 r_2} > 0 = \frac{r_1 - r_2 + g_c^2 r_1^2 r_2}{g_c^2 r_1^3 r_2} > 0$$

or $r_1 - r_2 + g_c^2 r_1^2 r_2 > 0$; from which

$$g_c^2 r_1^2 > \left[\frac{r_2 - r_1}{r_2} = 1 - \frac{r_1}{r_2} = 1 - a \right] \quad (7.1)$$

where

$$\frac{r_1}{r_2} = a; \text{ and } a > 1 - g_c^2 r_1^2 \quad (7.2)$$

Since $g_c^2 r_1^2$ is positive, then from (7.1)

$$a \leq 1 \quad (7.3)$$

Since a is positive, then from (7.2)

$$g_c^2 r_1^2 \leq 1 \quad (7.4)$$

or since

$$r_1 = 1/|g_o| \left(\frac{g_o}{g_c} \right)^2 \leq 1 \quad (7.4.1)$$

The circuit is stable for 7.3 and 7.4.1 when $1+g_o r_1 = 0$

(X) POWER GAIN, BANDWIDTH, AND NOISE FIGURE WHEN $1+g_o r_1 = 0$

(A) Power Gain G_p

From (4.8)

$$G_p = \frac{r_g}{r_1} \left[\frac{2g_o r_1}{(1+g_o r_1) (1+g_o r_2) - g_c^2 r_1 r_2} \right]^2$$

Insert $1+g_o r_1 = 0$, then $g_o = -1/r_1$, and

$$G_p' = 4/g_c^2 r_1 r_2 \quad (8.1)$$

let $r_g = r_1$, then $G_p' = 4/g_c^2 r_1 r_2$

let $r_2 = r_1/a$, then

$$G_p' = 4a/g_c^2 r_1^2 \quad = 4a(g_o/g_c)^2 \quad (8.2.1)$$

It is seen from (8.2) that a low value of g_c results in a high value for the power gain G_p' . However, this may result in a high noise figure if $1+g_o r_1$ is not exactly zero, as shown by:

$$N_F = 1 + 20I_o r_1 + \frac{(1+g_o r_1)^2}{g_c^2 r_1 r_2} (1 + 20I_o r_2) \quad (5.2)$$

This close adjustment required to make $1+g_o r_1 = 0$, makes it desirable to maintain a fairly high value of g_c and therefore a low value of G_p . In addition, it may be desirable to use a low value of local oscillator swing (E_o) to reduce the excursion in the value of g_o about its value at E_b .

(B) Bandwidth BC

From (4.5)

$$BC = \frac{(1+g_o r_1) (1+g_o r_2) - g_c^2 r_1 r_2}{(1+g_o r_2) r_1}$$

insert $1+g_o r_1 = 0$, then $g_o = -1/r_1$, and

$$BC = -\frac{g_c^2 r_1 r_2}{\left(1 - \frac{r_2}{r_1}\right) r_1} = g_c^2 r_1 \frac{r_2}{r_2 - r_1} \\ = g_c^2 r_1 \frac{1}{1 - \frac{r_1}{r_2}} \quad (8.3)$$

$$= \frac{g_o^2}{g_o} \frac{1}{1 - \frac{r_1}{r_2}} \quad (8.3.1)$$

(C) Sample values

Values of $g_o g_c$ and I_d were computed for tunnel diode 1N32218 for different values of E_b and E_o . From these values, the power gain, BC product, and noise figures were calculated from Equations 8.2; 8.3; and 6.1. Some values, which result in stable operation, are shown in the table of FIGURE 11.

(XI) SUMMARY

The system noise figure of a tunnel diode converter is expressed in Equation 5.2. If the quantity $1+g_o r_1$ of this equation is equal to zero, it will be seen that the noise figure will be reduced. Expressed in another manner, the noise figure is reduced because the negative resistance diode permits the gain of the system to be adjusted so that the noise originating at I-F is converted to signal frequency and back to I-F in an amplitude to equal the originating I-F noise component. Since the originating I-F noise current and the converted and reconverted component are in phase opposition, they cancel.

The quantity g_o is a function of the bias voltage amplitude and the amplitude of the local oscillator voltage applied to the tunnel diode 18 as will be seen from FIGURE 19. The quantity r_1 includes the input circuit 12 impedance as well as that of the signal source 10.

When $1+g_o r_1=0$ the noise figure of the converter is a function of the ratio of the average conductance g_o to the D.-C. current through I_o the diode. Increasing values of $|g_o/I_o|$ are shown in column 6 of FIGURE 11. It will be seen from column 9 of FIGURE 11 that the noise figure is minimum for the largest absolute value of g_o/I_o .

Column 10, of FIGURE 11 shows the noise figure when $1+g_o r_1=\pm 0.1$. In this case Equation 6.4 shows that the noise figure is not only a function of the ratio $|g_o/I_o|$, but also is a function of the ratio $(g_o/g_c)^2$. From column 10 it will be seen that the best noise figures occur for the operating conditions specified in lines 8 and 9 wherein the ratio $(g_o/g_c)^2$ is at a near minimum for reasonably large values of the ratio g_o/I_o .

In accordance with one embodiment of the invention, the bias voltage and oscillator drive are adjusted to provide the largest value for the ratio $|g_o/I_o|$ where g_o is negative. g_o may be made negative by biasing the diode in the negative resistance portion of its characteristic. The input resistance r_1 , including that of the input circuit 12 and signal source 10, is then adjusted to a value where $1+g_o r_1=0$.

With the particular germanium diode whose characteristics are shown in FIGURES 10 and 11, a D.-C. bias voltage of .12 volt is applied to the diode in a manner to permit stable biasing in the negative resistance region of the current-voltage characteristic. The peak oscillator voltage is .01 volt producing an average conductance of -6.8 mho. The input resistance r_1 including the resistance of the input circuit 12 and the signal source 10 is $1/6.8$ ohms. Thus the quantity $1+g_o r_1$ is equal to zero. This permits optimum noise operation of the frequency converter.

In accordance with a second embodiment of the invention, where the quantity $1+g_o r_1$ cannot be maintained exactly zero because of expected circuit tolerances or the like, this quantity is maintained as small as possible, but

the operating voltages may be different from those specified above to prevent degradation of the noise figure when the quantity $1+g_o r_1$ does not exactly equal zero. Under these conditions, the operating voltages applied to

5 the diode are adjusted to provide a low value for the quantity $(g_o/g_c)^2$ consistent with a reasonably high value for the quantity $|g_o/I_o|$. It will be noted from column 7 of FIGURE 11 that $(g_o/g_c)^2$ has low values for lines 1-3 and for lines 8 and 9. However the values for $|g_o/I_o|$ in lines 1-3 is very small, but is quite large for lines 8 and 9. Accordingly the operating voltages used are those specified in lines 8 and 9 with the input resistance r_1 adjusted to provide as low a quantity $1+g_o r_1$ as possible. For the operating conditions specified in lines 8 and 9, the noise figure 10 of the converter drops from 4.2 to 4.5 when the quantity 15 $1+g_o r_1$ changes from zero to ± 0.1 , whereas considerably poorer noise figure results in both cases for the operating conditions specified in lines 1-3 of FIGURE 11.

It is seen from Equation 3.7.2 that the input conductance 20 G_1 can be positive, zero, or negative by suitable choice of parameters. It is often desirable to make the input conductance as low as possible, and by adjusting the circuit parameters of Equation 3.7.2 the input conductance may be made as low as necessary.

25 What is claimed is:

1. A tunnel diode mixer circuit which is optimized for low noise operation comprising in combination, a tunnel diode, a signal input circuit for signals of a first frequency coupled to said tunnel diode, a signal output circuit for 30 corresponding signals of a second frequency coupled to said tunnel diode, means providing a source of local oscillations coupled to said tunnel diode, means providing a source of direct current biasing voltage coupled to said tunnel diode to forward bias said diode in the negative, 35 resistance region of its current-voltage characteristic, the amplitude of said biasing voltage and said local oscillations being such as to provide a conversion conductance g_c and a negative average conductance $(-g_o)$ and a direct current through the diode I_o wherein a near minimum value for the ratio $(g_o/g_c)^2$ is achieved for a near maximum value for the ratio $-g_o/I_o$.

2. A tunnel diode mixer circuit as defined in claim 1 wherein said signal input circuit has an equivalent resistance r_1 of a value so that the quantity $1+g_o r_1$ is substantially equal to zero.
